UNITED STATES PATENT OFFICE.

WILLIAM J. CAREY, OF NEW YORK, N. Y.

DESIGN FOR A RING.

No. 39,309.

Specification for Design.

Patented May 19, 1908.

Application filed November 13, 1907. Serial No. 401,960¹. Term of patent 14 years.

To all whom it may concern:

Be it known that I, WILLIAM J. CAREY, a citizen of the United States, residing at 210 West One Hundred and Thirty-third street, in the borough of Manhattan of the city of New York, county and State of New York, and having a place of business at No. 3 Maiden Lane, in the said borough of Manhattan of the city of New York, in the aforesaid county and State, have invented a new, original, and ornamental Design for Rings, of

which the following is a specification, reference being had to the accompanying drawing, forming a part thereof.

The figure is a plan view of a ring, showing my new design.

I claim:

The ornamental design for a ring as shown.

WM. J. CAREY.
